UNITED STATES PATENT OFFICE

WILLIAM R. GREER, JR., OF WOODHAVEN, NEW YORK, AND ERNEST A. WALKER, OF NEWARK, NEW JERSEY, ASSIGNORS TO ORANGE LIGHTING FIXTURE MANUFACTURING CO., A CORPORATION OF NEW JERSEY

DESIGN FOR A CHANDELIER BODY

Application filed November 25, 1929. Serial No. 33,554. Term of patent 7 years.

To all whom it may concern:

Be it known that we, WILLIAM R. GREER, Jr., and ERNEST A. WALKER, citizens of the United States and residents, respectively, of Woodhaven, county of Queens and State of New York, and Newark, county of Essex, State of New Jersey, have invented a new, original, and ornamental Design for a Chandelier Body, of which the following is a specification, reference being had to the accompanying drawing, forming a part hereof.

In the drawing:

Figure 2 is an inverted plane view of the same, the part shown in full line outline being ornamented in the same manner as the part more fully illustrated.

We claim:

The ornamental design for a chandelier body substantially as shown and described.

WILLIAM R. GREER, JR.
ERNEST A. WALKER.
